[57]

ABSTRACT

An improved copying machine for processing light-desensitizable transfer material and heat sensitive receiving material, comprising an exposure plate with a contact pressure cover, a heating device and a storage and take-up reel each for the band shaped transfer material. The effect of the heat of the heating device on the assembly of sheets comprising transfer and receiving material may be reduced or interrupted downstream of the matter to be transferred.

COPYING MACHINE

The invention is based on a method such as described for example in U.S. Pat. No. 3,049,417. Here a light sensitive sheet is first desensitized at points backed by an original by means of reflex exposure and is then heated in surface contact with a sheet of receiving material. This produces thereon a visible reproduction of the original by a reaction between the remaining not desensitized elements of the transfer material and the reactive substances in the surface of the receiving material.

A machine for carrying out this method and described in U.S. Pat. No. 3,318,219 provides the heating device in the form of a surface heater under the exposure mechanism. Thus, not only the exposure but also the heating takes place in the stationary state. For this reason a two step method is used, in which the transfer material is provided in the form of a continuous band passing over the exposure plate and through the heating device, whilst the original must be applied to one side of the exposure plate until it rests on the same. Contact pressure is then accomplished by means of a contact pressure cover and the exposure takes place. Then the band of transfer material is transported on until the exposed section is located within the heating device, and simultaneously a sheet of receiving material is applied, whilst the original has previously been detached. Then a contact pressure plate of the heating device is pressed on until the development is complete. After raising the contact pressure plate, the original is ejected on one side and the transfer material is reeled back until the end of the exposed section is at the input edge of the exposure plate. This long return results from the fact that together with the application of an unexposed section of the transfer material band, the original should also be carried along to the exposure plate.

This known device operates slowly because it comprises stationary operating stages. In addition, the long return of the transfer material requires considerable time. If thick originals are to be copied with the known device, which is not quite easy in view of the feed device for the original, special measures must be taken for raising the contact pressure cover.

The return of the strip shaped transfer material does not produce in itself an acceleration of the processing because excessive losses of transfer material are to be avoided. If, for example, a transport through a heating device were taken into consideration which must affect the material layers uniformly and for a certain period, this would have the disadvantage that the heat would also affect as yet unexposed sections of the transfer material, thereby rendering the same useless.

It is therefore an object of the invention to provide a copying machine which has a simpler construction and operates faster. According to this invention this object is realized by devices which reduce or prevent the heating device from applying heat to the zone of the assembly of sheets comprising transfer and receiving material behind graphic matter to be reproduced. Surprisingly, this enables the copying machine to be operated continuously in the zone of the heat applying device because the application of heat may be interrupted although the transfer material continues to move.

In a preferred embodiment of the invention the devices comprise a transport arrangement passing over a convex heating plate and having one or several conveyor belts passing over at least two rollers and adapted to be pivoted about a pivot located on the side of an outlet in order gradually to raise the conveyor belt or belts off the heating plate. The side of the outlet is remote from the exposure plate. By raising the conveyor arrangement, the contact pressure is simultaneously released and it should be noted that the conveyor arrangement is preferably such that with contact pressure the transfer material coming from the exposure plate is deflected downwardly. A high raising velocity may be accomplished by a more or less strong curvature of the heating plate. Owing to the raising, the trailing edge of the contact zone moves towards the side of the outlet of the apparatus. Preferably, the conveyor belt or belts are elastic, or the reversing roller remote from the pivot and located in a frame is resiliently mounted in order to tension the belts.

In another preferred embodiment, the said devices have a heat shield, pivotable about a pivot and curved concentrically to the pivot, and the heating device is a curved heating plate, the curvature of which is also concentric to the pivot, wherein the heat shield is adapted to be moved from the side of the exposure plate over the heating plate and an arrangement of conveyor belts is mounted on the heating device and raisable therefrom, so that the heat shield can be moved between the conveyor arrangement and the heating plate. In this arrangement, the heat shield can accurately limit the effects of the heating device of the heating plate.

Preferably the pivot is coaxial to a hollow shaft forming the core for the take up reel of the transfer material. In this manner, a particularly favorable compact arrangement may be produced.

In a particularly preferred embodiment of the invention, the movable transport device or the heat shield are movable as a function of the passage of the copy sheet, wherein either the lifting off the heating plate or the insertion of the leading edge of the heat shield (as viewed during the screening movement) are controlled in accordance with the trailing edge of the graphic matter to be transferred. In this manner only the surface section of the transfer material carrying an exposed reproduction is affected by the heat, acting on the layer.

In an embodiment in which the strip shaped transfer material is supplied after the passage of a copy by the rereeling of the storage reel and uncoupling of the receiving reel, in a convenient embodiment of the invention the reverse transport of the transfer material is accompanied by a return movement of the heat shield towards the exposure plate. This has the advantage that the exposure device is screened in addition to the heating device in the non-operating state and that an excessive heating of the heat shield is avoided. Preferably, the inside of the heat shield is mirror plated. In another embodiment a blower or fan may be provided for cooling the heat shield in the retracted position. Where a pivotable transport device is used, the same remains preferably in the raised position after the passage of a copy.

In another preferred embodiment of the invention, the contact pressure cover contains a stack holder with a stack of copy sheets adapted to be carried into a guide track as a function of a movement of the cover. This results not only in a surprisingly compact arrangement but has also the advantage that the receiving material may be guided immediately behind the take-off end of the exposure plate, thereby substantially reducing the re-reeling distances for the transfer material. Another advantage is in the operation because any special manipulations for supplying the receiving material are eliminated.

In another preferred embodiment of the invention, for supplying the receiving material the cover has, in fixed relation to its pivot, a drive wheel for a sheet delivery of the stack holder and a wheel driven by the main drive and located in the path of the said drive wheel when the cover is raised, is mounted on the housing so that the drive wheel meshes operationally when the cover is raised. In this manner, receiving material is supplied when the cover is raised. In this arrangement it is assumed that during an exposure the contact pressure cover rests in the lower position on the exposure plate, i.e., on the original, whether a sheet or a book, and is then raised for withdrawing the original.

Protection against the transport of the receiving material, for example, when inserting the original, is achieved in that the engagement between the wheel and the drive wheel takes place only when the cover is fully raised. According to an additional feature, the housing is provided with a spring abutment for the raised cover which engages the cover just before the drive wheel engages the wheel. This spring abutment provides a warning to the operator and indicates the point up to which the cover can be raised without causing a sheet of copying material to be transported. This transport of copying material is initiated only by overcoming the force of the spring abutment.

Preferably, the weight of the cover in the raised position is practically unimportant so that the operator does not have to overcome an excessive force for depressing the spring abutment. Drive wheel and wheel may be constructed as gears and may have a certain tooth clearance in order to facilitate the engagement, because the further steps are initiated only if the copying material reaches a certain position. Preferably, however, drive wheel and wheel are friction wheels.

In yet another embodiment of the invention, a continuously driven pair of transport rollers is mounted downstream of the sheet delivery for transporting the copying material after the same leaves the stack. In this manner, accurately defined actuating conditions are achieved even if the rollers are driven only for short periods. This embodiment is preferred because the operator may be instructed to keep the cover in the raised position against the force of the spring abutment, for example, only for 2 seconds.

In another preferred embodiment, a contact switch is mounted in the path of the receiving material and switches on the drive for the take-up reel of the transfer material for a certain time, after which the storage reel may be actuated for a reverse rotation over a certain path as a function of the standstill of the take-up reel. Also this produces automatic operation in accordance with the movement of the cover, i.e., as a function of

the feed-in of the copy material; here the release of the transport for the transfer material as a function of the advance of the copy material is particularly convenient because accurate synchronization may be achieved without retaining the copy material in a certain ready position outside the stack.

Conveniently, the pivotable transport arrangement and the heat shield are adapted to be actuated as a function of the operation of the contact switch through a delay element for lifting or for overlapping the heating plate for a certain period, and wherein the movement can be reversed and the heat shield returned in conjunction with the reverse rotation of the storage reel. Obviously, a timing control is possible in this connection only where certain sizes are used also for the reproductions. An adaptation is possible by correspondingly varying the time constants of the timing control. Since the transport arrangement remains preferably in the raised condition after one copy, in another preferred embodiment a movement of the pivotable transport arrangement can be initiated so as to press on the heating plate after an exposure as a function of the raising movement of the cover; when the contact pressure position has been reached a switch is operated which energizes the circuit for the motor of the transport arrangement to lift the same, wherein this circuit is preferably controlled by the stop switch. Care should be taken that the contact pressure position is reached comparatively quickly. This is possible without difficulties if the feed of the copy material is released mechanically by the movement of the cover. With operation of the contact by the start of the cover movement, a delay may be included for the transport of the receiving material.

Obviously, the invention may also comprise a switching roller control which may comprise cams arranged around the periphery to determine the timing in conjunction with a decentralized electric drive or may actuate linkages or levers of a mechanical control arrangement.

The invention will be further described by way of example with reference to two embodiments shown in the accompanying drawings in which:

FIG. 1 is a diagrammatic side elevation of a machine according to the invention in cross-section, showing the functionally necessary parts;

FIG. 2 is a cross-section of another embodiment of the invention corresponding to FIG. 1;

FIG. 3 is a diagrammatical partial view of FIG. 1;

FIG. 4 is a diagrammatical side elevation of the withdrawing roller;

FIG. 5 is a partial plan view in cross-section of FIG. 5, explaining the drive elements for the cover movement;

FIG. 6 is a cross-section along the line VI—VI in FIG. 5;

FIG. 7 is a circuit diagram of an embodiment of an actuating circuit.

In all Figures, identical parts are marked with the same reference numerals.

The machines shown in FIGS. 1 and 2 comprise a housing 1 with an exposure plate 2 arranged on top above a chamber 3 containing exposure light sources 4. On the left edge of the exposure plate 2 (as viewed in the drawing), a contact pressure cover 5 is hinge-

mounted; this contact cover 5 is shown in both Figures in the raised position. Its base has a resilient contact pressure plate 6, which may be supported by spring means and can adapt itself to an original. The cover is hollow and contains a stack holder with a stack 7 of copy sheets. The stack is mounted on a plate 90 which is hinge-mounted at 91. The other end of the plate is pressed upwardly by a spring 92, thereby pressing the top sheet against abutments 93 provided only at the corners.

In the zone of the pivots 8 of the cover, located on both sides of the housing (see also FIG. 5) and positioned near the forward upper end of the stack 7, a withdrawing roller 10, pivotable about a swivel arm rests under resilient pressure on the stack, so that the contact pressure is the same irrespective of the inclination of the cover. The pivot axis 8 is mounted on lateral raised plates 63 of the machine, as shown in detail in FIG. 5. These plates are not shown in FIG. 1 for reasons of clarity.

On the side of the exposure chamber 3 remote from the pivot 8, a storage reel 11 for a web of transfer material is mounted rotatably about a shaft 94. This reel is connected with drive means, not shown in detail, which can be uncoupled, or may cause after their deactivation a slight braking of the storage reel 11 in the direction opposite to its driven rotation. The storage reel is driven in a clockwise direction.

Preferably the storage reel is associated with a pair of guide rollers, 12, 13, driven by the main drive of the apparatus; these rollers are mounted in the housing and carry the transfer material to the exposure plate 2.

On the other side of the chamber 3 receiving roller 14 for the transfer material is mounted rotatably about a shaft 95. Also here, drive and coupling means are provided which drive the roller 14 preferably in an anticlockwise direction and entrain the transfer material. Also in this case the drive means have preferably a slight braking action in the opposite direction when they are switched off.

In the adjacent housing wall 96 there is a delivery slot 15 next to which is a collecting trough 16 for the developed copy.

Reference is now made to FIG. 1 in which the cover located on the exposure plate 2 is shown at 5' and indicated by broken lines. An upwardly convex curved heating device in the form of a heating plate 17 is mounted substantially above the roller 14; the length of the heating plate 17 is sufficient to affect the material passing the same for a sufficiently long period of time, having regard to its speed. The heating plate 17 is firmly mounted in the housing 1.

The arcuate heating plate 17 is associated with a transport device comprising two reversing rollers 18, 19 over which pass one or several conveyor belts 20. The reversing roller 18, located on the outlet side of the machine, has a quill shaft 21 through which it may be rotated by means of a drive motor 22 (FIG. 3). The quill shaft contains a rotary shaft 23 on which is mounted a pivoting arm or frame 24 on the ends of which the reversing roller 19 is mounted, for example, in slots 25 under bias by springs 86 away from the reversing roller 18, so that the conveyor belt 20 are always under tension. Thus, the reversing roller 19 can be pivoted by the frame 24 as indicated by the arrow 26

in FIG. 1, thereby lifting the conveyor belts 20 off the heating plate. To this end the shaft 23 may carry a pinion 27 (FIG. 3) which meshes with the gearing of a gear motor 28 or, as shown in FIG. 1, a lifting mechanism 97 with a rack 29 and a gear drive 30 may act on the end of the pivotable part of the frame. The gear drive has a motor 98 driving via gears 99 a pinion 100 which meshes with the rack 29.

Owing to the curvature of the heating plate, when the transport arrangement 18-20, 24 is moved in the direction of the arrow 26, the conveyor belts are gradually lifted off the end of the heating plate facing the exposure plate 2.

Behind the pivot 8 of the cover, there is mounted in the housing of the machine at least one continuously driven pair of transport rollers, comprising rollers 31, 32 which receive the copy material from the withdrawing roller 10. This pair of transport rollers may be preceded by a further pair of transport rollers 34, 35 mounted on the cover in front of the stack holder and behind an inlet guide element 33 and a contact switch 36 is located between the two pairs of transport rollers and is actuated by the leading edge of the copying sheet supplied from the stack 7. The guide and transport roller 12, 13, 31, 32 define with their uniform diameters the transport speed of the materials, including particularly also the transport material because an exclusive control by means of rollers 11 and 14 would require additional control elements in view of their varying diameters, e.g., by circumferential scanning.

The web shaped transfer material 37 is supplied from the storage reel 11 over the exposure plate 2 via the pair of transport rollers 31, 32 to the roller 14 in such a manner that it does not affect the contact switch 36.

When, as described further below, the cover is raised by means of the handle 38 after an exposure, the copy material is guided from the stack 7 between the transport rollers 34, 35, 31, 32, and causes the contact switch 36 to be actuated. In this manner, the drive motor for the pairs of rollers 31, 32, and 12, 13 is switched on so that the leading edge of the copying material is applied with the leading edge of the exposed section of the transfer material and the assembly comprising the transfer material and the copy material is carried under the conveyor belts 20 along the heating plate. When the trailing edge of the sheet of copy material reaches the reversing roller 19 (FIG. 1), the passage of this edge over the heating plate causes the start of the lifting movement of the transport arrangement 18-20, 24 in the direction of the arrow 26 so that no unexposed part of the transfer material is heated. The transport continues until the copy sheet has been deposited in the trough 16, then the drive of the roller 14 and of the pairs of rollers 31, 32 and 12, 13 is reversed and that of the storage reel 11 is switched on until the exposed edge of the trailing section of the transfer material has passed the left hand edge of the exposure plate 2 as viewed in FIG. 1. Then the drive for the rollers 31, 32, 12, 13 and storage reel 11 is automatically switched off. The working strokes may be carried out under timing control for different sizes of reproductions in the manner just explained. Details will be explained further below with reference to a control arrangement shown in FIG. 7. It should be mentioned that it is important to operate the withdrawing roller 10 only after making an exposure.

As shown in FIG. 2, a heating device in the shape of a heating plate 39 is arranged concentrically to the core of the take-up reel 14 constructed as a quill shaft 101. This quill shaft which is mounted in the housing carries a rotary shaft 40 for lateral sectors 41. These sectors carry a heat shield 42 adapted to be moved in the direction of the arrow 43 in a reciprocating manner. This may be carried out for example by means of a pinion mounted adjacent to the quill shaft on the rotary shaft 40 and meshing with a rack drive. The heat shield 42 has a curvature which is also concentric to the shaft 40 but so spaced therefrom that it can be pivoted to cover the outside of the heating plate 39. The outside is provided with an arrangement of three transport rollers 44, 45, 46, mounted in the housing and supporting conveyor belts 47. The transport roller 45 may be driven in a clockwise direction whilst the rollers 44, 46 are resiliently held in contact by means of springs 48, 49. They can lift off when the heat shield 42 is placed in position between the transport arrangement and the heating plate.

Instead of the lifting of the transport arrangement 18-20, 24 described with reference to FIG. 1, in FIG. 2 the left edge of the heat shield 42 follows the trailing edge of the copy sheet and prevents thereby the heat from affecting unexposed transfer material. In this construction the heat shield 42 is returned to its starting position during the reverse transport of the transfer material 37, to prevent unnecessary heating.

In the arrangement of FIG. 2 a continuously driven pair of transport rollers 50, 51 is mounted, for example, pivotably on the cover. A guide element 52 located on the cover behind this pair of rollers carries a contact switch 53 adapted to be actuated by the leading edge of a copy sheet coming from the stack 7 for control purposes.

A particularly simple system for supplying the copy sheet material is shown in FIGS. 1 and 4 to 6 and may also be used for the FIG. 2 arrangement. The withdrawing roller 10 is connected, e.g., by a belt drive, with a drive wheel 56 mounted on one side in the cover, as indicated in FIG. 1. The housing 1 contains a wheel 57 continuously driven by the main drive and located in the path of the drive wheel 56 moved with the cover 5, so that it engages the drive wheel 56 when the cover is fully raised. This causes the withdrawing roller to be operated when the cover is raised to transport a sheet of copy material from the stack 7.

Furthermore, one side of the cover has an abutment with spring 58 which makes contact with an abutment 59 of the cover just before engagement between the wheels 56 and 57 is established; preferably both these wheels are friction wheels.

The operator has to hold the cover 5 only for a short time in the fully raised position, overcoming the resistance of the spring 58, until the leading edge of the copy sheet enters between the transport rollers 34, 35. In view of the compact construction this only takes a fraction of a second.

The drive wheel 56 is shown in FIGS. 4 and 5. It is associated with a pulley 60 mounted on the same shaft 102 and connected by a belt 61 with a further pulley 62 mounted on a shaft 54 serving simultaneously as pivot for the swing arms 9. The shafts 102 and 54 are mounted in the cover 5, shown only partly in FIGS. 4 and 5. The stack 7 in the cover 5 is also shown partly in

FIG. 5 and carries the withdrawing roller 10. The swing arms 9 are provided with a gearing 103.

FIGS. 4 and 5 also show the pivot 8 of the cover on one side thereof. As indicated in FIG. 5 this pivot is only arranged in the zone of side plates 63 on both sides of the housing and projecting therefrom at the top. A cover side wall 64 serves simultaneously as mounting plate for the shaft 102 of the drive wheel 56 and carries an abutment 65 for the spring abutment 66 shown diagrammatically in FIG. 5. The abutment 65 may be located just in front of the pivot 8 of the cover and is inclined to the upper side of the cover and to the pivotable end of the cover, so that it encounters the spring abutment substantially vertically when the cover is raised.

It is obvious that the spring abutment may be made adjustable so that the operator may adjust both the timing and the strength of the actuation.

The circuit diagram of FIG. 7 has main terminals 71, 72. Behind a main switch 106 there is first a circuit 107 with the main motor 108 of the machine to which are connected through gearings 109 continuously driven components, such as pairs of rollers 34, 35, the disk 57 or the pair of rollers 51, 50. In addition, the exposure device 4 is located between the terminals 71, 72 and is adapted to be switched on by a switch 70.

Contact switch 53, 36 is connected between the current terminals in series with a delay action relay 73. This relay closes a contact 74 in the drive circuit 75 for the take-up reel 14. This drive unit also actuates other associated drive elements such as the reversing roller 18. The delay of the relay 73 is so dimensioned that this drive 75 stops after the necessary transport path. At the moment of stopping a contact 76 possibly using the switching movement of the delay action relay 73 but operating as a function of the stopping of the drive 75, closes a circuit for a further delay action relay 77, the switching contact 78 of which actuates the transport device 79 of the storage reel 11 for the timed re-reeling. The operating element for the contact 76 is shown at 110. The switching relationship is such that the transition of the drive 75 from movement to standstill and the opening of the relay contact 74 collaborate to effect the short duration closure of the contact 76 to release the transport device 79 which remains switched on in accordance with the timing element of the relay 77.

During this process, in FIG. 1, the transport arrangement 18-20, 24 must first be lowered from the raised position and then again be raised in a certain relation to the working cycle. To this end, the transport device 29, 30 (FIG. 1) or 27, 28 (FIG. 3) or a corresponding drive

for the shaft 40 (FIG. 2) are provided which must be reversible. Starting from the position of FIG. 1 in which the transport mechanism is first in the raised position, it may be lowered by raising the cover 5. To this end, a switch 80 is provided which is actuated during the lifting of the cover by means of a stop or by acting on its handle 38 so that the switching arms 81, 82 are positioned in such a manner that the transport mechanism is lowered by means of the motor 28 or 98.

The switch contacts for this drive are indicated by the letter a.

It should be noted that the contact switches 53, 36 are also connected to a circuit 105 comprising a relay

85 with delayed energization and de-energization, the contact 84 of which is located in the circuit 104 which also contains the switching arms 81, 82 of the switch 80. A parallel circuit 106 for the switch contact 84; the switch 107 of this circuit is connected by a linkage 108 with the switch 80. Consequently, when, during the raising of the cover the switching arms 81, 82 are moved into the position *a*, the bypass circuit 106 is closed making possible the lowering movement of the transport device. The lowest position of the transport device may be fixed by a limit stop 83 in the zone of the transport device 29, 30 or 27, 28. When contact is made with this limit stop, the switching arms 81, 82 are switched to the other transport device and rest on switch contacts *b*, whilst the circuit 106 is open. In this manner, the circuit for the transport device is now, i.e., for the raising, controlled only by the relay 85. The timing element of the relay 85 is such that the lifting movement of the transport device starts when the trailing edge of the picture reaches the reversing roller 19. In this manner, the transport device 27, 28, 29, 30 is actuated at the right moment and for the right duration. When the relay 85 has been de-energized and the cover is in the starting position with the machine inoperative, the transport device 18-20, 24 remains first in the top position. For a new working cycle the cover movement moves the switching arms again into contact with the switch contacts *a* and closes the circuit 106.

If, as described above, the movement of the cover is also used for controlling the transport device 29, 30 or 27, 28, the actuation is preferably interlocked with the exposure 4. For example, the exposure circuit may contain a relay 67 with delayed de-energization, the switch contact 68 of which is connected in series with the circuit of the contact switches 36, 53. For example, this contact 68 may also be connected in series with the other control circuits with the relay 77 and the transport device 79.

With regard to FIG. 2, it should be stated that when the cover is first moved, nothing happens because the movement of the heat shield 42 takes place only when the relay 85 is energized. When this relay is de-energized, the drive circuit for the heat shield is automatically reversed to return the heat shield. A return circuit, not shown in detail, may be automatically interrupted by a contact switch. In addition, this return circuit is automatically switched off in the case of an exposure to make possible the forward drive of the heat shield 42.

I claim:

1. An improved copying machine for processing light-desensitizable transfer material and heat sensitive copying material, comprising a housing having a delivery slot for delivering the copy, wherein the improvement comprises an exposure plate on the upper side of the housing on which exposure plate an original may be fitted, a contact pressure cover pivotally mounted on said housing for pressing an original against said exposure plate, a storage reel located within said housing and spaced outwardly from one edge of said exposure plate, a take-up reel located within said housing and spaced outwardly from said exposure plate on the opposite side thereof from said storage reel, said storage reel and take-up reel arranged to receive the transfer material in the form of a con-

tinuous web, exposure light sources positioned within said housing underneath said exposure plate, a plate-shaped heating member disposed within said housing adjacent said take-up reel and arranged for the passage of transfer and copying materials thereover, and movably displaceable means situated within said housing adjacent said plate-shaped heating member, said movably displaceable means being arranged for movement relative to said plate-shaped heating member as a function of the passage of the transfer and copying materials over said heating member.

2. A copying machine as set forth in claim 1, wherein the heating member is an upwardly convexly curved heating plate over which the transfer and copying materials are guided and wherein said movably displaceable means comprises a transport arrangement positioned above said heating plate and includes a frame containing two rollers arranged so that they rest on the opposite edges of said heating plate, at least one elastic conveyor belt passes over these two rollers and the frame has at the end remote from said exposure plate a pivot, and drive means for pivoting the frame about the said pivot, thereby lifting the said at least one conveyor belt gradually, starting with the edge of the heating plate facing said exposure plate.

3. A copying machine as set forth in claim 2, wherein the pivot of the pivoting frame is arranged concentrically to a roller, and the frame also comprises spring means for tensioning the conveyor belt.

4. A copying machine as set forth in claim 1, wherein the heating member is an upwardly convexly curved heating plate over which the transfer and receiving materials are guided and said movably displaceable means comprising as a moving element a curved heat shield mounted on a shaft located in the housing, wherein the curvature of the heat shield corresponds to that of the heating plate and the shaft is so arranged that the heat shield can be moved directly above the heating plate, and further comprising a transport arrangement associated with the heating plate and adapted to be elastically lifted thereoff so that the heat shield can be moved between said transport arrangement and said heating plate.

5. A copying machine as set forth in claim 4, wherein the take-up reel is mounted on a quill shaft through which the said shaft for the heat shield passes coaxially, and wherein the heating plate and the heat shield are curved concentrically to the take-up reel.

6. A copying machine as set forth in claim 4, wherein the inside of the heat shield is mirror-plated.

7. A copying machine as set forth in claim 1, wherein a first drive motor is connected to the storage reel and a second drive motor to the take-up reel and switching means are provided in the circuits of the motors whereby the switching means switch the first and the second drive motor alternatively so that after one exposure, first the second motor is switched on for moving a set of copying and transfer material over the heating device, wherein the passage of the rear edge of the copy material in the heating device operates a movable element forming a portion of the said displaceable means comprising a liftable arrangement of conveyor belts and a movable heat shield and wherein after the passage of the copy material past the heating device the first motor is switched on and re-reels the web-shaped transfer material back to the storage reel.

8. A copying machine for processing light-desensitizable transfer material and copying material with the copying material supplied as sheets, comprising a housing, a developing unit and an exposure unit positioned within said housing, said exposure unit including an exposure plate located on the top of said housing and a contact pressure cover pivotally mounted on the top of said housing and arranged to cover said exposure plate for positioning an original on said exposure plate, a drive for the copying machine for feeding the transfer and copying materials therethrough, wherein the improvement comprises a stack holder containing a stack of copying sheets located within said pressure cover, and withdrawing means within said contact pressure cover in contact with the stack of copying sheets therein for removing sheets individually from the top of the stack, and drive elements arranged in operative engagement with both of said drive for the copying machine and said withdrawing means when said cover is pivoted away from said exposure plate.

9. A copying machine as set forth in claim 8, wherein the contact pressure cover is mounted on a pivot, a first drive wheel is provided adjacent to the pivot and is located in the housing and continuously driven by the machine drive, the withdrawing means located in the cover and acting on the top sheet comprises a withdrawing roller, a second drive wheel for this withdrawing roller is provided on the cover, said drive elements are provided between the withdrawing roller and the second drive wheel so that it engages during the movement of the cover the said first drive wheel for actuating the withdrawing roller.

10. A copying machine as set forth in claim 9, wherein the housing has a spring abutment for the raised cover and engaging the cover just before the second drive wheel engages the first drive wheel.

11. A copying machine as set forth in claim 9, wherein the said first and second drive wheels are friction wheels.
